WILLIAM J. HORSTMANN, OF PHILADELPHIA, PENNSYLVANIA.

Letters Patent No. 95,112, dated September 21, 1869.

IMPROVEMENT IN LET-OFF AND TENSION-DEVICES FOR SPOOLS OF BRAIDING-MACHINES.

The Schedule referred to in these Letters Patent and making part of the same.

To all whom it may concern:

Be it known that I, WILLIAM J. HORSTMANN, of Philadelphia, Pennsylvania, have invented an Improved Let-Off Motion for the Spools of Braiding and Other Machines; and I do hereby declare the following to be a full, clear, and exact description of the same.

My invention relates to the mechanism employed for letting off the yarn from the spools of braiding-machines; and

My improvement consists of devices whereby the uniform tension on the yarn is maintained, and the ready removal and replacement of the spools or bobbins facilitated.

In order to enable others skilled in the art to make and apply my invention, I will now proceed to describe its construction and operation, reference being had to the accompanying drawing, which forms a part of this specification, and in which—

Figure 1 is a side elevation of my improved let-off motion;

Figure 2, the same, partly in section;

Figure 3, a vertical section on the line 1-2, fig. 2;

Figure 4, a section plan on the line 3-4, fig. 2; and

Figure 5, a side view of one of the let-off motions in common use.

Similar letters refer to similar parts throughout the several views.

In reference to figs. 1, 2, 3, and 4, A is a spool, such as is used in braiding and plaiting-machines or rotary looms, and this spool is so fitted over a vertical spindle, B, as to turn freely thereon, under the circumstances referred to hereafter, the spindle projecting from a base, D, on the machine, from which base also projects a vertical guide, E, for the sliding weight F, the latter and the guide being so adapted to each other, that the slide can move up and down freely without turning.

In the annular upper edge of the spool A are formed ratchet-teeth *a*, between which engages a pawl, G, consisting of an arm hung loosely at one end to the upper end of the spindle B, the opposite end projecting into and fitting, so as to move freely in, a slot, *e*, in the guide E.

The thread or yarn *x*, from the spool, passes through a hole, *f*, in the guide E, thence downward between the said guide and the sliding weight F, round the lower edge of the latter, and upward outside the same, and through an eye, *y*, in the upper end of the guide E, to the point where the several yarns of the machine are braided, plaited, or woven together.

As seen in fig. 2, the spool is locked by the pawl G, and hence, as the thread or yarn is drawn off, the sliding weight F must be elevated while it imparts the desired tension to the thread. As the sliding weight approaches the limit of its upward movement, its pro-

jecting lip *h* comes in contact with the under side of the said pawl G, and raises the same until it is free from the ratchet-teeth of the spool, when, owing to the tension of the yarn, the spool must turn and let off more yarn. Simultaneously with this turning of the spool, however, the sliding weight descends, and with it the pawl G, which, catching against another ratchet-tooth, arrests the motion of the spool until, by a continued drawing off of the yarn, the weight is again brought in contact with the pawl, and another supply of yarn is delivered from the spool, the sliding weight, throughout these movements, continuing to impart the desired tension to the yarn.

In one form of let-off device heretofore used, and shown in fig. 5, the pawl G is arranged to slide on the guide E, and is elevated through the medium of the sliding weight F, by the yarn, as the latter is being drawn off.

The moment the sliding weight is brought into contact with the pawl, the weight of the latter is added to that of the slide, and consequently the tension of the yarn is increased. More than this, a lateral strain is imparted to the pawl by the yarn, through the medium of the spool; hence the socket is brought into such frictional contact with the guide as to impede its free upward movement. Thus the uniformity of the tension is interrupted from time to time, partly by the increased weight of the pawl, and partly by the friction of the latter against the guide, and the consequent sudden increase of tension is the frequent cause of breaking the thread or of imperfect work.

This evil is obviated in my improvement by hinging to the spindle a pawl, G, so light and delicate as to be readily raised, the end of the pawl being guided by the slot *e*, so that its free movement cannot be impeded by the bearing against it of the teeth of the ratchet, which would turn it to one side, and wedge it in the slot in the spindle B.

Other forms of let-off devices have pawls hung at a point above the spool, but in such a manner that the spool cannot be withdrawn without first breaking the thread or removing the pawl, thus requiring much labor and manipulation in changing or rearranging the bobbins.

I claim as my invention, and desire to secure by Letters Patent—

The arrangement of the pawl G on the ratchet-bobbin spindle B, in respect to the guide E, having a slot, *e*, opening *y*, and weight F, as described.

In testimony whereof, I have signed my name to this specification, in the presence of two subscribing witnesses.

WM. J. HORSTMANN.
